UNITED STATES PATENT OFFICE.

WALTER H. WILLIAMS, OF DETROIT, MICHIGAN.

DESIGN FOR A BOTTLE.

SPECIFICATION forming part of Design No. 35,165, dated October 8, 1901.

Application filed September 10, 1901. Serial No. 74,958. Term of patent 7 years.

To all whom it may concern:

Be it known that I, WALTER H. WILLIAMS, a citizen of the United States, residing at Detroit, in the county of Wayne and State of Michigan, have invented and produced a certain new and original Design for a Bottle, of which the following is a specification, reference being had therein to the accompanying drawings, in which—

10 Figure 1 is a perspective view of the bottle, and Fig. 2 is a plan view thereof.

A is the body portion of the bottle, having a substantially octagonal base, one diameter thereof being greater than the diameter perpendicular thereto. The sides *a*, separated by the greater diameter, are of convex form, while the sides *b*, separated by the lesser diameter, are flat and parallel. Intermediate the sides *a* and *b* are the inclined flat sides *c*.
20 At its upper end the body *A* terminates in a

neck *B*, having the concaved lower portion *d*. The sides *a*, *b*, and *c* intersect with this portion *d* to form the scalloped lines *e*, *f*, and *g*. The neck *B* is provided with a flat rib *h* at its upper end and below this with rounded ribs 25 *i*, *j*, and *k*.

The leading feature of the design is the body having the octagonal base, one diameter of which is greater than the other diameter, the sides having the greater diameter being convex and the other sides being flat. 30

What I claim as my invention is—

The design for a bottle, substantially as herein shown and described.

In testimony whereof I affix my signature 35 in presence of two witnesses.

WALTER H. WILLIAMS.
